UNITED STATES PATENT OFFICE

CECIL C. PECK, OF LAKEWOOD, OHIO, ASSIGNOR TO THE HILL CLUTCH MACHINE AND FOUNDRY COMPANY, OF CLEVELAND, OHIO, A CORPORATION OF OHIO

AGITATING MECHANISM

Application filed December 30, 1929. Serial No. 417,367.

This invention, relating as indicated to agitating mechanisms, has specific reference to agitating mechanisms adaptable to be used as pulp digesters or to accomplish like objects.

In a pulp digester or like agitating mechanism, in order to secure a complete agitation or digestion of every portion of the body of the material it is essential that the mechanism be so constructed that no pockets or dead ends occur in which some of the material may be segregated. In order to properly agitate large quantities of materials it is also a necessary feature of the construction of the agitating mechanism that the streams of materials set up therein effect a movement of every portion of the body of material. It is therefore an object of my invention to provide an agitating mechanism which shall have the above-named desirable features.

In the construction of agitating mechanisms capable of accommodating large quantities of materials, such constructions, where any attempt has been made to bring about a proper distribution of the material therein, are costly to the point of being impractical. In order to bring about the proper relationship between the various elements of the agitating mechanisms now commonly employed huge castings have been used which, as before mentioned, are costly to manufacture, as well as exceedingly cumbersome during installation. It is an object of my invention to provide a structure in an agitating mechanism which shall have the advantages of low cost and ease of construction, as well as being readily adaptable to the unique form which the parts of such mechanism must of necessity assume. Other objects of my invention will appear as the description proceeds.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various mechanical forms in which

the principle of the invention may be used. In said annexed drawings:—

Fig. 1 is a plan view of the agitating mechanism comprising my invention; Fig. 2 is a broken sectional elevation of the mechanism illustrated in Fig. 1; Fig. 3 is a fragmentary perspective view of the connection between the upper and lower portions of the wall of the inner chamber; and Fig. 4 is a fragmentary section of mechanism illustrated in Fig. 2 taken on a plane substantially indicated by the lines 4—4.

Referring more specifically to the drawings, and more especially to Figs. 1 and 2, the agitating mechanism here illustrated consists of a substantially cylindrical tank or vat 1 which is formed of a hollow cylindrical shell filled with concrete or other like material, as most clearly shown in Fig. 2. The outer shell 2 has a substantially flat bottom 3, and the bottom of the inner shell 4 is substantially concave and formed in the manner hereinafter to be more fully described. The bottom plate 5 of the inner shell 4 is of such size as to leave a substantial opening in what would normally be the lower corners of the tank. Through this opening the concrete is poured from which the base of the tank is formed, and after such concrete has been filled to the point indicated at 6 a plurality of closure means 7, such as tiles, are laid on such concrete to present a symmetrical and smooth fillet for the lower corners of the outer cylindrical chamber.

Positioned on the upper end of the wall of the cylindrical tank 1 are plural transversely extending sills 8 which support the agitating mechanism. The sills 8 support the cross members 9, which in turn support a motor 10. The sills 8 likewise support cross members 11, on which are mounted the differential gear housing 12. The differential gear housing 12 has a shaft 13 extending laterally therefrom, to which shaft is rigidly secured the pulley 14. The pulley 15 carried by the shaft 16 of the motor 10 and the pulley 14 are suitably interconnected by flexible driving means 17. The differential gear housing 12 has depending therefrom a tu-

bular member 18 which is secured thereto by means of the coupling 19 and which encompasses the vertically disposed drive shaft 20.

- 5 The bottom of the outer cylindrical chamber 1 has mounted therein a plurality of spaced circularly disposed legs 21 which are formed with stream line proportions, as most clearly shown in Fig. 1. These legs 21 10 are mounted on suitable enlarged bases 22 which give adequate support for the legs 21 in the concrete forming the bottom of the outer cylindrical chamber 1. Positioned on the legs 21 and rigidly secured thereto by 15 means of the bolts 23, are a plurality of segmental elements 24, which have radially extending flanges 25. The segmental elements 24 are united to form a bowl-like object 26 by means of the bolts 27 passing through 20 the flanges 25. The bowl-like object 26 forms the lower portion of the inner tubular chamber which is formed at its upper portion by the circular plate 28. The circular plate 28 is likewise formed of a plurality 25 of sections which are connected, as most clearly shown in Fig. 4, to the vertically disposed column members 29. The columns 29 are preferably formed of channel members 30 and 31 which are suitably joined as at 32 by welding or otherwise. The space enclosed by the channel members 30 and 31 is then filled with concrete as at 33 to act as a preservative, as well as a reinforcing means. The columns 29 are secured to the cross sills 34 which are carried by the sills 8. 35 The bowl-like object 26 forming the lower portion of the tubular chamber has a restricted opening 35 formed in the bottom thereof which is bounded by the annular 40 convex wall 36, which along with the outer wall 37 of the bowl 26 forms a receptacle for the concrete 38 which fills this space, as shown in Fig. 2. After the space has been filled with concrete the tiling or like material 39 is placed on the face of the concrete, which tiling affords a smooth surface for the interior of the bowl, as well as presenting a wearing surface much superior to the bare concrete. The bowl 26, when 45 formed in the above described manner, provides a smooth surface leading to the restricted aperture 35 formed in the bottom thereof so that there is no possibility of pockets or recesses in which material may 50 become segregated. 55

The bottom 5 of the outer cylindrical chamber 1 has positioned thereon a pedestal 40, which is in the form of a cone having a concave slope, and the screws 41 embedded 60 in the concrete forming the bottom of the large tank offer additional means for securing the pedestal in place. The pedestal 40 may preferably be hollow and likewise filled with concrete as at 42 to effect a strengthening 65 of the pedestal as well as providing a

preservative for the inner surface thereof. The pedestal 40 is centrally adapted to receive bushing 43, which is secured thereto by means of the plate 44 and the bolts 45. Bushing 43 is adapted to revolvably support 70 the terminal portion 46 of the depending shaft 20. Embedded in the concrete forming the base of the outer chamber is a conduit member 47 by means of which material may be introduced to, or withdrawn from 75 the tank.

Rigidly secured to the shaft 20, is a propeller 48, here shown consisting of three blades, although any other suitable form may be employed to accomplish the same 80 results. The propeller 48 is so positioned on the shaft 20 that it is slightly below the horizontal plane of maximum convexity of the wall 36, so that upon rotation of the propeller the stream of material set up thereby 85 will be directed in a radial as well as an axial direction. It will be noted that maximum efficiency of the propeller 48 along the lines above mentioned will be obtained when the propeller is positioned as described, however, a somewhat different positioning of the propeller may be utilized to effect similar 90 results.

The relative sizes of the inner tubular chamber and the outer cylindrical chamber 95 is such that the volume of the inner chamber is only slightly larger than the volume of the space enclosed between the inner wall and the wall of the outer chamber. This relation 100 between the relative sizes of the two chambers is particularly advantageous from the standpoint of securing the proper movement of the material contained therein as it passes downwardly through the restricted aperture 35 and up around the space 105 enclosed between the walls forming the two chambers and then spills over the outer edge 49 of the plate 29 back into the tubular chamber.

The concave formation of the bottom of the cylindrical chamber, along with a complementary formation of the bottom of the tubular chamber, makes the volume of the space between the walls forming the two chambers uniform throughout its entire 110 length. The uniformity in volume of this space insures a uniform condition of flow in every portion of the agitated body of material. The formation of the pedestal 40 in the shape of a cone having a concave slope 115 assists in maintaining this uniformity of the volume throughout the space between the two chambers, as well as a diverting means which assists the propeller 48 in imparting a radial flow to the material passing down through the restricted aperture 35.

By forming the bowl 26 in the manner described, the necessity of a large core casting, which would be very expensive, is entirely done away with. The concrete 38 will be 120

poured after the body of the bowl 26 has been installed, thereby greatly reducing the labor incidental to such installation, and the tiling 39 which is used to face the concrete

5 affords a protective covering for such concrete as well as an inner surface for the bowl which is much smoother than could be attained by the use of concrete alone. The formation of the concave bottom of the outer shell in the manner described is also particularly advantageous for the same reasons attributed to the peculiar construction of the bowl 26. The filling with concrete of the space enclosed by the channels 30 and 10 15 31 forming the column 29 materially assists in reinforcing such columns, as well as preserving the interior thereof. If the columns 29 were not filled with a material such as concrete a certain amount of moisture would 20 find its way into such columns, resulting in a rapid deterioration thereof, necessitating frequent and expensive replacements.

It will be seen from an examination of the above outlined structure that an agitating mechanism such as is commonly used in agitating pulp is attained which has advantages not found in any constructions now commonly employed.

Other modes of applying the principle of 30 my invention may be employed instead of the one explained, change being made as regards the mechanism herein disclosed, provided the means stated by any of the following claims or the equivalent of such 35 stated means be employed.

I therefore particularly point out and distinctly claim as my invention:—

1. In a mechanism of the character described, the combination with a cylindrical 40 chamber, of a tubular chamber having a restricted opening at the bottom thereof positioned coaxially therein, the wall of said tube around such opening progressively thickened to provide a smooth curve to said 45 restricted opening, and means for producing a flow through said restricted opening from one of said chambers to the other.

2. In a mechanism of the character described, the combination with a cylindrical 50 chamber, of a tubular chamber having a restricted opening at the bottom thereof positioned coaxially therein, the wall of said tube around such opening progressively thickened to provide a smooth curve to said 55 restricted opening, and means positioned in said restricted opening for producing a flow of material therethrough from one of said chambers to the other.

3. In a mechanism of the character described, the combination of a cylindrical 60 chamber; a tubular chamber positioned coaxially within said cylindrical chamber; a restricted opening in the lower end around said tubular chamber, the wall of said 65 restricted opening being annular and convex

and filled with concrete; and means for producing a flow of material through said restricted opening from one of said chambers to the other.

4. In a mechanism of the character described, 70 the combination with a cylindrical chamber; a tubular chamber positioned coaxially within said cylindrical chamber; a restricted opening in the lower end around said tubular chamber, the wall of said restricted opening being annular and convex; an aperture in said wall for filling said wall with concrete; and means for producing a flow of material through said restricted opening from one end of said chamber to 80 the other.

5. In a mechanism of the character described, 85 the combination with a cylindrical chamber; a tubular chamber positioned coaxially within said cylindrical chamber; a restricted opening in the lower end of said tubular chamber, the wall around said restricted opening being annular and convex; an aperture in said wall for filling said wall with concrete; means for closing said aperture when said wall has been so filled; and means for producing a flow of material through said restricted opening from one of 90 said chambers to the other.

6. In a mechanism of the character described, 95 the combination of a cylindrical chamber; a tubular chamber positioned within said cylindrical chamber; means secured to the lower portion of said tubular chamber, said means including a plurality of segmental elements adapted to form a restricted opening in the lower end thereof, a hollow annular convex wall surrounding said aperture, a circumferential aperture in said wall for filling the same with concrete; and means 100 for closing said circumferential aperture to present a smooth face to said wall; and means for producing a flow of material through said restricted opening from one of 105 said chambers to the other.

7. In a mechanism of the character described, 110 the combination of a cylindrical chamber having a concave bottom; a hollow wall for said chamber; a circumferential aperture in the concave portion of said wall 115 for filling the same with concrete; means for closing said aperture when so filled, said closure means presenting a smooth face for said wall; a tubular chamber positioned within said cylindrical chamber; legs having stream-line proportions for sustaining said tubular chamber within said cylindrical chamber; and means for producing a flow of material from one of said chambers 120 to the other.

8. In a mechanism of the character described, 125 the combination of a cylindrical chamber; a tubular chamber positioned coaxially within said cylindrical chamber, said tubular chamber including a plurality of 130

segmental members rigidly secured to vertically disposed hollow members filled with concrete; means associated with the lower end of said tubular chamber for presenting a restricted opening thereto, said means including a plurality of segmental members having radially extending longitudinally disposed ribs by means of which said segmental members are joined; and legs having stream-like proportions for sustaining said tubular chamber, said legs, ribs and hollow members in vertical alignment.

9. In a mechanism of the character described, the combination of a cylindrical chamber, a tubular chamber positioned within said cylindrical chamber, a restricted opening formed in one end of said tubular chamber, an annular convex wall bounding said restricted opening, a propeller shaft vertically disposed in said tubular chamber, a pedestal in the form of a cone having a concave slope positioned in the bottom of said cylindrical chamber and axially aligned with said restricted opening, a bearing carried by said pedestal for supporting said shaft, and a propeller mounted on said shaft in said restricted opening for originating a radially and axially directed stream of material through said opening.

33 Signed by me, this 28th day of December, 1929.
